UNITED STATES PATENT OFFICE.

HARLEY M. JOHNSON, OF CHICAGO, ILLINOIS.

ANTI-FRICTION JOURNAL-BEARING.

SPECIFICATION forming part of Letters Patent No. 402,599, dated May 7, 1889.

Application filed March 21, 1888. Serial No. 267,947. (No model.)

To all whom it may concern:

Be it known that I, HARLEY M. JOHNSON, a citizen of the United States, residing at Chicago, in the county of Cook and State of Illinois, have invented certain new and useful Improvements in Anti-Friction Journal-Bearings, of which the following is a specification, to wit:

This invention relates to an improvement in anti-friction journal-bearings; and it consists in certain peculiarities of the construction and arrangement of the same, substantially as will be hereinafter more fully set forth and claimed.

15 In order to enable others skilled in the art to which my invention pertains to make and use the same, I will now proceed to describe its construction and arrangement, referring to the accompanying drawings, in which—

20 Figure 1 is a central longitudinal section of my device. Fig. 2 is a cross-section on the line $x-x$, Fig. 1; and Fig. 3 is a cross-section on the line $y-y$, same figure.

a represents the frame or casing in which 25 the whole journal-bearing is inclosed, and may of course be of any form suitable to the work to be done and the position it is to occupy. In the present instance it is shown as a car-axle box. The axle or shaft b is passed into 30 the casing, and around the journal are ar- ranged a series of anti-friction rollers, b' , which bear upon the journal all the time. The ends of these rollers are shouldered or turned down, as at b^2 , and enter recesses in 35 a circular boxing, c , at each end, and each of these roller-journals is also provided with a series of very small rollers, c' , arranged around it and filling the space between the large roller and the recesses in the boxing. This

40 will be well shown in Fig. 2, where the face of the boxing is removed to fully show the small rollers. The two circular boxes in which the large rollers are journaled are secured together by longitudinal braces or bars d , se- 45 cured by nuts d' on their ends, as in the drawings. The main body of these bars may be of any form in cross-section; but I prefer the triangular form herein shown, as giving a firmer shoulder against the circular boxes c and 50 holding them with more rigidity and less liability of the whole bearing being twisted in

action. The usual brass, d^2 , is used in the axle-box and lies between the circular box- 55 rings c , as shown.

The end of the axle-box a , or casing at the front, is formed in line with the axle with a projection, e , and in both it and the end of the axle are formed holes or sockets, into which is loosely received the rod or spindle e' . The adjoining faces or ends of the axle and 60 the projection e are formed with circular grooves e^2 , and between the axle and projection are placed two, three, or more small wheels, e^3 , which are held on radial studs f of the spindle, and serve to take the end-thrust 65 of the axle or shaft without friction.

It will be at once understood that this device is well adapted to any position or purpose without material change, and that as the shaft revolves the rollers revolve also, and 70 without slip or friction, as their revolution amounts simply to a travel across the curved face of the brass or bearing, and as the journals of these rollers are held in the circular boxes, they are not only separated and kept 75 from contact with each other, but they are also provided with roller-journals, and the friction is thus reduced to the last degree. No strain is borne upon these small rollers, and the bearing is thus strong and not liable to 80 get out of repair.

The end-thrust of the shaft is readily taken by the small friction-wheels on the recessed spindle, and no friction or grinding of the parts can occur. The edge form, size, and number 85 of these wheels will be changed as deemed ad- 80 visable in particular cases; but the principle here shown will not be departed from.

Having thus fully described my invention, what I claim as new, and desire to secure by 90 Letters Patent, is—

1. In a roller-bearing, the combination, with a series of large rollers for engaging the shaft, journaled in suitable revolving circular boxes, of a series of small rollers placed in these 95 boxes around each of large roller-journals, substantially as and for the purpose set forth.

2. The combination, with a journal box or casing provided with a socketed projection on its inner side and a shaft in line therewith, 100 and also formed with a longitudinal socket, the ends of both the shaft and projections be-

ing provided with concentric grooves, of a spindle with projecting bearings, socketed loosely in said parts, and a series of anti-friction wheels on said spindle running in said grooves, substantially as and for the purpose set forth.

3. The combination, with a shaft having its ends formed with a concentric groove, and a projection on the journal box or casing with a circular groove aligned with the shaft, of a series of small friction-wheels placed between the shaft and projection and running in said grooves, substantially as and for the purpose set forth.

15. In a journal-bearing, the combination, with a casing having a socketed projection

formed with a circular groove in its face, and a shaft also formed with a socket and groove, of a series of rollers arranged around the shaft, each of which is also provided with a roller-journal at each end in a revolving circular boxing, and a loose spindle with projecting bearings socketed in the shaft and the box projection and provided with a series of small wheels to take the end-thrust, substantially as shown, and for the purpose set forth. 20 25

In testimony whereof I affix my signature in presence of two witnesses.

HARLEY M. JOHNSON.
